US00D927573S

(12) **United States Design Patent** (10) **Patent No.:** **US D927,573 S**
(45) **Date of Patent:** **** Aug. 10, 2021**

(54) **CUTTING INSERT**

(71) Applicant: **Korloy Inc.**, Seoul (KR)

(72) Inventors: **Young Heum Kim**, Cheongju-si (KR); **Hyo San Kim**, Cheongju-si (KR); **Min Seok Oh**, Cheongju-si (KR); **Nam Seon Lee**, Cheongju-si (KR); **Ki Chan Nam**, Cheongju-si (KR)

(**) Term: **15 Years**

(21) Appl. No.: **35/509,191**

(22) Filed: **Jan. 20, 2020**

(80) **Hague Agreement Data**

Int. Filing Date: **Jan. 20, 2020**

Int. Reg. No.: **DM/207209**

Int. Reg. Date: **Jan. 20, 2020**

Int. Reg. Pub. Date: **Apr. 24, 2020**

(30) **Foreign Application Priority Data**

Sep. 18, 2019 (KR) 30-2019-0044789

(51) **LOC (13) Cl.** **15-09**

(52) **U.S. Cl.**

USPC **D15/139**

CPC **B23C 5/207** (2013.01)

(58) **Field of Classification Search**

Primary Examiner — Richard E Chilcot

(74) Attorney, Agent, or Firm — Rabin & Berdo, P.C.

(57) **CLAIM**

The ornamental design for a cutting insert, as shown and described.

DESCRIPTION

1. Cutting insert
- 1.1 : Perspective
- 1.2 : Front
- 1.3 : Back
- 1.4 : Top
- 1.5 : Bottom
- 1.6 : Left
- 1.7 : Right

1 Claim, 7 Drawing Sheets
